CLAIM

The ornamental design for a portable grill, as shown and described.

DESCRIPTION

FIG. 1 is a left side elevational view of a portable grill showing our new design, the right side being a mirror image thereof;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view of a second embodiment;

FIG. 7 is a right side elevational view the left side being a mirror image thereof;

FIG. 8 is a top plan view thereof;

FIG. 9 is a bottom plan view thereof;

FIG. 10 is a front elevational view in which the lower half of the grill kettle has been broken away for the convenience of and illustration; and,

FIG. 11 is a rear elevational view thereof.
